UNITED STATES PATENT OFFICE

EVELYN JAHNCKE, OF NEW ORLEANS, LOUISIANA

DESIGN FOR LADIES' HAND-BAG

Application filed June 24, 1932. Serial No. 44,190. Term of patent 7 years.

To all whom it may concern:

Be it known that I, EVELYN JAHNCKE, a citizen of the United States, residing at New Orleans, parish of Orleans, and State of Louisiana, have invented a new, original, and ornamental Design for Ladies' Hand Bag, of which the following is a specification, reference being had to the accompanying drawing, forming part thereof.

In the drawing:—

Fig. 2 is a rear perspective view.

I claim:

The ornamental design for ladies' hand bag as shown.

In testimony whereof, I affix my signature.

EVELYN JAHNCKE.
